DESIGN FOR A SHOE SOLE

Norman Everett Bovay, Naugatuck, Conn., assignor to Sport Products, Inc., Cincinnati, Ohio, a corporation of Ohio

Application November 19, 1945, Serial No. 123,904

Term of patent 14 years

(Cl. D54—12)

To all whom it may concern:

Be it known that I, Norman Everett Bovay, a citizen of the United States and a resident of Naugatuck, in the county of New Haven and State of Connecticut, have invented a new, original, and ornamental Design for a Shoe Sole, of which the following is a specification, reference being had to the accompanying drawing which forms a part thereof.

In the drawing:

Figure 1 is a bottom plan view of a shoe sole showing my new design.

Figure 2 is a sectional view as would appear if taken along the line 2—2 in Figure 1.

I claim:

The ornamental design for a shoe sole, substantially as shown.

NORMAN EVERETT BOVAY.
